UNITED STATES PATENT OFFICE.

FRANK HEDLEY, OF YONKERS, AND JAMES S. DOYLE, OF MOUNT VERNON, NEW YORK.

STREET-SWEEPING MACHINE.

1,202,062.

Specification of Letters Patent. Patented Oct. 24, 1916.

Application filed October 14, 1914. Serial No. 866,609.

To all whom it may concern:

Be it known that we, FRANK HEDLEY and JAMES S. DOYLE, both citizens of the United States, and residents, respectively, of Yonkers and Mount Vernon, in the county of Westchester and State of New York, have made a certain new and useful Invention in Street-Sweeping Machines, of which the following is a specification.

10 This invention relates to street sweeping machines.

The object of the invention is to provide an apparatus of the nature referred to which is simple in construction, economical to 15 manufacture, easy to operate, and efficient in operation.

A further object is to provide a street sweeping apparatus wherein is employed a rotary sweeper carried by a frame in such 20 manner that said sweeper may be swung laterally and horizontally from one side to the other of the frame on which it is mounted.

Other objects of the invention will appear more fully hereinafter.

25 The invention consists substantially in the construction, combination, location and relative arrangements of parts, all as will be more fully hereinafter set forth, as shown in the accompanying drawings, and finally 30 pointed out in the appended claims.

In the drawings: Figure 1 is a view in top plan of a sweeping apparatus embodying the principles of our invention, positions of the 35 rotary sweeper on opposite sides of the carrier frame being indicated in dotted lines. Fig. 2 is a view in side elevation of the same. Fig. 3 is a view in horizontal section on the line 3, 3, Fig. 2, looking in the direction of the arrows, parts broken off.

40 It is a common practice to employ rotary sweepers mounted upon frames which are propelled along the streets to be swept, or along track rails of street car systems, the sweeper being suspended underneath the 45 carrier frame and ordinarily disposed in a generally transverse position across the frame and in a transverse direction to the line of travel or propulsion of the frame.

In the operation of such sweepers, so arranged, a comparatively limited area is covered, and where such a machine is employed to clean snow or dirt along the tracks of a street car system, for instance, the result is to leave the snow or dirt swept from the 55 path of the sweeper piled up in a line paral-

lel and closely adjacent to the track rails, making it difficult and inconvenient for passengers to board or alight from cars operating along the track system. Moreover if the sweeper is arranged to extend beyond the 60 sides of the carrier frame in which it is mounted, on one side or the other thereof, the vehicle which carries the sweeper must be turned around at the end of the line in order to enable the sweeper to operate at the 65 opposite side of the track on the return trip, and in many instances it is inconvenient or undesirable to turn the vehicle.

It is among the special purposes of our present invention to provide a carrier 70 designed to operate on the track rails of a street car system and to mount thereon a rotary sweeper in such manner as to permit the sweeper to be rocked or swung into position to project or extend beyond either side 75 of the carrier without disturbing or interfering with the drive gearing through which the rotary brush is operated, thereby enabling the apparatus to clear away snow, rubbish or the like from the immediate 80 vicinity of the track rails, the brush operating on one side of its carrier vehicle while said vehicle is moving in one direction and on the other side while moving in the opposite direction.

85 While the principles of our invention may be carried out in many specifically different embodiments, without departure from the spirit and scope of the invention as defined in the claims, we will describe one arrangement as illustrative of the principles involved and which we have found to be simple and efficient.

In the construction shown A. designates a vehicle which, in the instance shown is 95 mounted on supporting wheels B. If desired, though not necessarily, the supporting wheels B may be truck wheels and may operate along the track rails C of a street railway system, the trucks being located at the 100 ends of the vehicle.

Intermediate its ends the body portion D of the vehicle A is elevated or arched, as clearly shown in Fig. 2, leaving the end portions E, with an open space F, between 105 them. Extending a short distance into the space F, from the base of one of the end compartments or portions E is a support G, in which and in the overhanging body part D is journaled a vertical shaft H. Mount- 110

ed upon shaft H to rock therewith is a frame J, portions of which extend on opposite sides of the shaft H. In one portion of frame J is journaled a horizontal shaft K which carries a rotary sweeper L. In the other portion of said frame is mounted a motor M, from which, through suitable gearing N, the sweeper shaft K may be rotated. The frame J, and the motor and sweeper devices and intermediate gearing are located and operate in the space F between the ends E of the vehicle carrier A. In order to enable the sweeper L to operate at one side or the other of the vehicle, as indicated in dotted lines in Fig. 1 it is only necessary to rock the frame J laterally and horizontally about the vertical axis of shaft H, in one direction or the other, as may be desired. This may be accomplished in many different ways, as, for instance, by attaching frame J to shaft H so as to rock therewith, and providing some means for rocking said shaft H. A simple arrangement is shown wherein shaft H is rocked axially by means of a small auxiliary motor P, through suitable gearing R, S.

In operation the sweeper L is liable to encounter rough or uneven surfaces, stones, cobbles or the like. In order to avoid damage or injury it is desirable to provide means whereby in such event, the sweeper may easily ride over or clear the obstruction. To this end we propose to mount the shaft H for vertical longitudinal movement through a desirable range. To permit such vertical movement of shaft H one or the other of the intermeshing gears S. R. may be provided with elongated teeth. By this arrangement it will be readily seen that when the sweeper L encounters an obstruction in its path the entire frame J can rise sufficiently to permit the sweeper to pass or ride over the obstruction, without interfering with the sweeper drive gearing or the gearing which rocks the frame J laterally. At the same time the weight of the frame J and of the parts carried thereby is imposed on the sweeper L to efficiently hold the same to its work. The motor M serves as a counter weight for the portion J of the frame which carries the brush L.

It will be readily seen that the provision of the open space F intermediate the wheel or truck supported ends of the vehicle affords a most convenient arrangement to permit the sweeper to be swung laterally and horizontally so as to project or extend beyond either side of the vehicle, and at any desired angle. Ordinarily, and in order to deflect the sweepings away from the vehicle, or, for instance, from the track rails, the sweeper will be somewhat inclined outwardly and rearwardly with reference to the direction of travel, and consequently it is unnecessary to turn the vehicle around

when the vehicle reaches the end of a line. All that is necessary to do to permit the sweeper to operate on the opposite side of the vehicle when the latter proceeds in the opposite direction on its return trip without turning around at the end of the trip is to swing the frame J to the other side of the vehicle and in similar outward and rearwardly inclined rotation with respect to the new line of travel of the vehicle. And this action does not even require a reversal of the motor M. While the car is being run along streets or tracks which do not require the operation of the sweeper and also while passing other vehicles occupying the street when the sweeper is in operation, the brush and its supporting frame will be swung into position underneath the car and therefore will not interfere with other street traffic.

Having now set forth the objects and nature of our invention and a construction embodying the principles thereof, what we claim as new and useful and of our own invention, and desire to secure by Letters Patent is,

1. In a street sweeping machine, a vehicle, a laterally movable supporting frame adapted to lie longitudinally under said vehicle and comprising oppositely extending portions, a sweeper carried by one of said extending portions of said frame and a motor carried on the other extending portion of said frame for driving said sweeper.

2. In a street sweeping machine, a vehicle, a vertically disposed shaft journaled therein, a frame carried by said shaft, a sweeper carried by said frame, means for rocking said frame horizontally to cause the same to project the sweeper at any desired angle with respect to said vehicle, and a motor carried on said frame for rotating said sweeper at any desired projected position thereof.

3. In a street sweeping machine, a vehicle, a sweeper carried by said vehicle and adapted to lie longitudinally under the same, means for swinging said sweeper horizontally out from either side of said vehicle and means to rotate said sweeper.

4. In a street sweeping machine, a vehicle, a vertically disposed shaft journaled therein, a frame carried by said shaft and adapted to lie beneath said vehicle, along the length thereof, means to rock said shaft to swing said frame horizontally out from the side of said vehicle, a sweeper carried by said frame, and means for rotating said sweeper.

5. In a street sweeping machine, a vehicle, a vertically disposed shaft journaled therein, a frame carried by said shaft and adapted to lie beneath said vehicle, along the length thereof, means to rock said shaft to swing said frame horizontally out from the side of said vehicle, a sweeper carried by

said frame, and means carried by said frame to rotate said sweeper.

6. In a street sweeping machine, a vehicle having an elevated or arched body portion, 5 a frame supported beneath the elevated or arched body portion of the vehicle, and normally lying longitudinally thereunder, means for swinging said frame about its support to project the same on either side of 10 said vehicle, a sweeper carried by said frame, and means to rotate said sweeper.

7. In a street sweeping machine, a vehicle having an elevated or arched body portion, a vertically disposed shaft journaled in said 15 vehicle in said elevated or arched body portion, a frame carried by said shaft and lying normally in a longitudinally disposed position under said elevated or arched body portion, means for rocking said shaft, a 20 sweeper carried in said frame, and means to rotate said sweeper.

8. In a street sweeping machine, a vehicle having an elevated or arched body portion,

a vertically disposed shaft journaled in said vehicle in said elevated or arched body portion, a frame carried by said shaft and lying normally in a longitudinally disposed position under said elevated or arched body portion, said frame comprising oppositely extending portions, a sweeper carried by one 25 of said extending portions, means for rotating said sweeper carried by the other of said extending portions, and means to rock said shaft to project said sweeper frame horizontally from under said elevated or arched 30 portion on either side of said vehicle.

In testimony whereof we have hereunto set our hands in the presence of the subscribing witnesses, on this 21st day of September, A. D. 1914.

FRANK HEDLEY.
JAMES S. DOYLE.
